INVENTOR
WILLIAM A. KEENEY

BY *W. A. Keeney*
ATTORNEY.

UNITED STATES PATENT OFFICE

WILLIAM A. KEENEY, OF WETHERSFIELD, CONNECTICUT, ASSIGNOR TO THE KEENEY MANUFACTURING COMPANY, A CORPORATION OF CONNECTICUT

VALVE

Application filed September 10, 1929. Serial No. 391,662.

My invention relates to valves.

It has for its object to provide an improved valve, and more particularly an improved valve adapted to use on radiators or the like.

5 A further object of my invention is to provide such an improved valve having improved controlling means for the air and moisture escaping prior to the shutting of the valve and wherein the difficulty with leakage blown out into the room is eliminated and a more clean and dry construction provided at the same time that the noise arising from the escaping air is also minimized. A further object of my invention is to provide 10 an improved valve having the advantages set forth, which further is a valve of the gravity opening type and is adapted to be kept at all times in the vertical position which insures its most effective operation. Still further objects of my invention include the provision of an improved and simplified valve structure, and such a structure which is adapted to be manufactured and assembled at small expense. These and other objects of my invention will, however, hereinafter more fully appear.

In the accompanying drawings I have shown, for purposes of illustration, one embodiment which my invention may assume in 30 practice.

In these drawings,—

Figure 1 is a side elevation of my improved valve attached to a radiator, the latter being shown in dotted lines;

35 Fig. 2 is a vertical longitudinal section of the valve;

Fig. 3 is a plan view of the valve;

Fig. 4 is a plan view of the base portion of the valve, the upper portion thereof being 40 removed to facilitate illustration;

Fig. 5 is a detail sectional view on line 5—5 of Fig. 2, and

Fig. 6 is an end view of the valve in position on a radiator, a plurality of other positions occupied during attachment also being 45 shown in dotted lines.

In this illustrative construction I have shown a valve comprising a usual casing 1 and having a valve aperture 2 carried in the 50 top thereof and controlled by a float 3 of

any usual expandible fluid type, which is movable vertically between the valve seat and a bottom support 4, herein carried within a casing base 5 which is in turn connectible to a radiator by a threaded projection 6 carrying a usual drainage tube 7.

In my improved construction, improved means are provided for controlling the discharge from the valve aperture 2. More particularly, it will be noted that while in this construction the flow is upward through a usual axial passage 8 in an adjustable member 9, herein threaded at 10 in a reduced extension 11 on the top of the member 1, improved means are provided acting in a new manner on the discharge from the passage 8. Herein, a top casing member 12 is provided, which is of substantially larger diameter than the member 9 and also has a closed top 13 spaced above the upper end of the passage 8 and vertical sides 14 spaced from the sides of the member 9 and herein extending substantially below the top of the latter. This casing member 12 is herein also provided with a small lateral outlet or port 15, herein 75 closely adjacent the base of the sides 14. Thus it will be noted that the flow through the valve aperture 2 is first directed upward against the top 13 and thereby caused to be diffused and reversed and passed down inside 80 the walls 14 and between the same and the member 9. Accordingly, the moisture contained in the flow is effectually separated and caused to flow down the vertical walls 14 of the member 12, while, due to the large area of 85 the chamber 16 provided and the relatively small size of the outlet 15, only a small portion of entrained liquid of condensation is expelled through the port 15 with the escaping air, while the latter also escapes quite 90 noiselessly.

Attention is further directed to the fact that improved moisture collecting and absorbing means are provided. Herein, it will be noted that the member 12 is also provided, 95 below its sides 14, with an annular outwardly extending flange 17 which is inclined slightly upward toward its outer periphery. This flange forms an annular groove adapted to intercept liquid flowing down from the aper-

ture 15. It will also be observed that I provide one or more, herein four, apertures 18 in this flange and spaced around the same, which lead downward and drain any caught liquid into the interior of a base 19 formed on the member 12. Further, I herein also provide in this base 19 and herein filling the latter and fitted on the reduced extension 11, a washer or washers 20, herein two, of a suitable absorbent material, such, for example, as an asbestos composition. Attention is here also directed to the fact that the base member 19 is substantially larger in diameter than the extension 11, while the walls 14 and 17 are also substantially spaced from that extension. Thus it will be observed that not only is the escape of liquid minimized, as previously described, but all liquid remaining in the chamber 16 is drained down the walls 14 and absorbed by the absorbent material, while escaping liquid is prevented from flowing down over the valve, the same instead being caught by the flange 17 and supplied through the apertures 18 to the absorbent material, all in such manner as to maintain a clean, dry valve.

In my improved construction, I have also provided improved inlet means and connections disposed at the opposite end of the float 30 from the means heretofore described. As shown herein, it will be noted that the support 4 is in the form of a pin suitably attached, as by soldering, in a recess in the top of a horizontal inlet member 21. This inlet member 35 21 herein is inserted as a unit through a suitable aperture 22 in the side wall of the portion 5 and suitably attached, as by soldering, to the side and bottom of that portion. Attention is also directed to the fact that this member 21 is of polygonal external cross section, and that the opening 22 is correspondingly shaped (see Fig. 5), all in such manner that the member 21 is thus locked against rotation relative to the portion 5 when inserted in the latter. It will, moreover, be noted that the bore 23 of this member 21 not only extends through its threaded connection 6 but is also provided with a top transverse slot or outlet 24 closely adjacent and beneath the float 3 and 40 between the support 4 and the threaded portion 6. It is also herein provided with an axial end aperture 25 on the opposite side of the support 4 from the slot 24 and adapted to receive condensation and permit its flow to the drainage tube 7. Attention is also directed to the fact that the pin 4 is extended into this bore 23 in such manner that it will engage with a flange 26 on the inner end of the drain tube 7 and accordingly act to prevent 45 the withdrawal of the latter, while leaving the tube free to move between the limits established by the pin and the adjacent edge of the axial aperture 25.

Attention is also directed to the fact that 50 herein I have provided upon the member 21

a threaded flange 27, preferably formed integral therewith, and disposed between the threaded portion 6 and the portion 5 and of slightly larger diameter than the aperture 22 and the portion 6. Attention is also directed to the fact that a rotatable locking member 28 is carried on the threads on the member 27 and adjustable thereon. Thus, it is made possible for my improved valve to be kept at all times in the vertical position wherein the float 3 operates most effectively, the locking member 28 acting to hold the valve in that position when the valve and this locking member are properly adjusted relative to one another and the radiator. More particularly, this construction makes it possible, when the valve is being threaded by its portion 6 into the usual tap hole in a radiator, to carry the valve as a whole beyond the vertical into the dotted line position shown at the right in Fig. 5, and then pull it back into the dotted line position shown at the left in that figure, whereupon the locking member 28 can be turned up tight and the valve thereafter moved into the desired vertical position shown in full lines, in which it is securely held against any accidental movement to one side or the other causing improper functioning of the float.

In the operation of my improved valve, it will be understood that, as usual in such valves, when the steam is turned on, the cold air in the radiator will enter the valve through the portion 6 and slot 24 and pass out of the casing 1 through the port 2, which will then be open, while, when the steam commences to flow, the float 3 will act to close the valve 2 and condensation within the casing 1 will flow out through the aperture 25. It will also be understood that the members 9 and 4 will preferably be soldered in their position and that the members 5, 12 and 21 will also be soldered. Considering the operation more particularly, it will be noted that due to the reversal of the flow and to the improved passage means provided between the valve aperture 2 and outlet aperture 18, the amount of liquid passing through the latter is substantially reduced at the same time that the operation of the valve is made more quiet. Further, it will be noted that due to the provision of the flange 17 and the apertures 18 in the latter, together with the absorbing means 19, the difficulty with escaping moisture is minimized while the drainage down the walls 14 is also absorbed, and the absorbent material is, of course, subsequently dried by the heat. Moreover, through my improved construction at the base of the float, it is made possible to use only a simple base 5 and member 21 and insert the latter as a unit laterally and simultaneously interlock it with the base 5 in the position in which it is desired to solder the parts together. Moreover, it will be noted that through the improved passages 24 and 25 in the member 21, that member is

rendered effective to supply heat directly and said absorbing means and having both an outlet above said absorbing means and communications with said absorbing means for liquid passing through said outlet and liquid remaining in said cover member.

6. A radiator valve comprising a casing, an air escape valve therein, a float controlling the latter, a float support carrying and inlet member insertable as a unit through the side of said casing below said float, and a float support carried by said member. 70

10 7. A radiator valve comprising a casing having an aperture in its side, an air escape valve in said casing, a float therein controlling said valve, a float support carrying and inlet member insertable as a unit through said aperture and interlocking with the walls thereof, and a float support carried by said member. 80

15 8. In a radiator valve comprising a casing, an air escape valve therein, a float controlling the latter, a float support carrying member insertable as a unit through the side of said casing below said float, said member having within the casing and beneath said float an upwardly opening air and steam supply, and a float support carried by said member. 85

20 9. A combined supply, drainage, and float support means for radiator valves, comprising an elongated member having a bore, a supply outlet leading from said bore, a drainage aperture leading to said bore, and a float support carried by said member. 90

25 10. A combined supply, drainage and float support means for radiators comprising an elongated member having a bore, a supply outlet leading from said bore, a drainage aperture leading to said bore, a float support, and a drainage tube engageable by the latter. 100

30 11. A combined supply, drainage, and float support means for radiator valves, comprising an elongated member having a bore, a supply outlet leading from said bore, a drainage aperture leading to said bore, a float supporting extending into the bore, and a drain tube in the bore limited in its movement by said support. 105

35 12. A radiator valve comprising a casing, a base therefor having an aperture in its side, an air escape valve in said casing, a float therein controlling said valve, an inlet member insertable as a unit through said aperture, a float support carried by said member, and interlocking rotation preventing means on said member and the walls of said aperture. 110

40 13. In a radiator valve, a valve casing, an air escape valve therein having a projecting outlet, absorbent material disposed around said valve below the outlet thereof, and enclosing means for said material and the valve outlet having a liquid separating dome enclosing the latter and communicating with said absorbent material and having a lateral 115

45 5. In a radiator valve, a casing having an air escape valve therein, absorbing means on said casing surrounding said valve, and a cover member of larger diameter than said valve enclosing the discharge thereof and 120

50 6. What I claim as new and desire to secure by Letters Patent is:—

55 1. In a radiator valve, a valve casing having an air escape valve therein and an outlet, and liquid absorbing means in said casing having communication with said outlet and receiving through said communication liquid escaping through said outlet. 125

60 2. In a radiator valve, a valve casing having an air escape valve therein and an outlet, liquid separating means between the same receiving the discharge from said valve, and liquid absorbing means in said casing having a communication with the separated liquid not previously passed out through said outlet, and also a communication with the liquid passed through the latter. 130

65 3. In a radiator valve, a casing having an air escape valve therein and an outlet, and liquid intercepting means intercepting liquid discharged through said outlet and having drain means leading therefrom into said casing.

70 4. In a radiator valve, a casing having an air escape valve therein and an outlet from said casing, liquid intercepting means adjacent said outlet intercepting liquid flowing out of the latter, absorbing means in said casing, and means for supplying thereto through said intercepting means the intercepted liquid.

75 5. In a radiator valve, a casing having an air escape valve therein, absorbing means on said casing surrounding said valve, and a cover member of larger diameter than said valve enclosing the discharge thereof and

While I have in this application specifically described one form which my invention may assume in practice, it will be understood that this form is shown for purposes of illustration only, and that the invention may be modified and embodied in various other forms without departing from its spirit or the scope of the appended claims.

30 30. What I claim as new and desire to secure by Letters Patent is:—

35 1. In a radiator valve, a valve casing having an air escape valve therein and an outlet, and liquid absorbing means in said casing having communication with said outlet and receiving through said communication liquid escaping through said outlet.

40 2. In a radiator valve, a valve casing having an air escape valve therein and an outlet, liquid separating means between the same receiving the discharge from said valve, and liquid absorbing means in said casing having a communication with the separated liquid not previously passed out through said outlet, and also a communication with the liquid passed through the latter.

45 3. In a radiator valve, a casing having an air escape valve therein and an outlet, and liquid intercepting means intercepting liquid discharged through said outlet and having drain means leading therefrom into said casing.

50 4. In a radiator valve, a casing having an air escape valve therein and an outlet from said casing, liquid intercepting means adjacent said outlet intercepting liquid flowing out of the latter, absorbing means in said casing, and means for supplying thereto through said intercepting means the intercepted liquid.

55 5. In a radiator valve, a casing having an air escape valve therein, absorbing means on said casing surrounding said valve, and a cover member of larger diameter than said valve enclosing the discharge thereof and

outlet therein above said absorbent material.

14. In a radiator valve, a valve casing, an air escape valve therein having a projecting outlet, absorbent material disposed around said valve below the outlet thereof, enclosing means for said material and the valve outlet having a liquid separating dome enclosing the latter and communicating with said absorbent material and having a lateral outlet therein above said absorbent material, and means in said enclosing means delivering to said absorbent material liquid passing out through said outlet.

15. In testimony whereof I affix my signature.
WILLIAM A. KEENEY.
